UNITED STATES PATENT OFFICE.

RICHARD BRADSHAW, OF TORONTO, ONTARIO, CANADA.

MATTRESS.

1,144,888.

Specification of Letters Patent. Patented June 29, 1915.

Application filed December 4, 1913. Serial No. 804,670.

To all whom it may concern:

Be it known that I, RICHARD BRADSHAW, of the city of Toronto, in the county of York, in the Province of Ontario, Canada, 5 have invented certain new and useful Improvements in Mattresses, of which the following is the specification.

My invention relates to improvements in mattresses and the object of the invention 10 is to provide means for preventing spreading of the mattress horizontally thus keeping it in normal shape and at the same time to provide means for preventing the gripping loops pulling out at the edges of the 15 mattress and it consists essentially of a plurality of bands extending freely crosswise and longitudinally of the mattress and above and below the mattress body, such bands being secured at the horizontal ends 20 only to the mattress cover, and gripping loops formed integrally with and connecting the upper and lower bands together as hereinafter more particularly explained by the following specification.

25 Figure 1, is a perspective view of the mattress intermediately broken away both longitudinally and crosswise. Fig. 2, is a vertical section through the mattress as shown in Fig. 1.

30 In the drawings like letters of reference indicate corresponding parts in each figure.

A is a mattress cover provided with a suitable filling A'.

B and B' are upper and lower bands extending across the mattress within the cover thereof above and below the filling. C and C' are similar bands extending at right angles to the bands B and B' within the cover 35 thereof and above and below the filling.

40 The bands B and B' and C and C' are connected at both ends to each other and to the cover by a suitable stitching 2 and 3. The bands B and B', C and C' extend at their

ends through the seams 4 and 5 of the mattress cover formed at the corners of the 45 mattress so as to form connecting loops B² and B³ and C² and C³. Preferably the bands B and B' and the end loops C² and C³ are formed in one strip of material, the ends 50 of which are connected together at 3. Similarly the bands C and C' and loops B² and B³ are formed in one strip. It will also be noticed that the bands B and B' and C and C' are located intermediately between the cross and longitudinal rows of the usual 55 mattress tufts thus allowing the free action of the bands from end to end independently of the mattress cover.

By connecting the mattress cover to the ends of the bands it will be readily seen 60 that it will be impossible for the mattress to spread in either direction horizontally so as to deform the shape of the mattress allowing it to become thin in parts. And also by forming the gripping loops integral with 65 the band the pulling out of these loops from the mattress cover is prevented.

What I claim as my invention is:

In a mattress, the combination with a mattress cover and a filling thereof, of a 70 plurality of longitudinal and cross surrounding bands extending above and below the mattress filling so as to form a lattice-like structure and connected to the mattress cover at the corner seam thereof, the band 75 portions extending above the mattress filling being connected by looped integral portions to the band portions extending below the mattress filling, such looped portions being exterior to the mattress cover, as and 80 for the purpose specified.

RICHARD BRADSHAW.
